(57) **CLAIM**

I claim the ornamental design for a reel for electronic components carrier tape, substantially as shown.

DESCRIPTION

FIG. 1 is a top view of the reel for electronic components carrier tape, showing its new design;

FIG. 2 is a side view thereof;

FIG. 3 is a bottom view thereof;

FIG. 4 is a perspective top view thereof; and,
FIG. 5 is a perspective bottom view thereof.
